(57) **CLAIM**

The ornamental design for a breath test ventilation apparatus, as shown and described.

DESCRIPTION

FIG. 1 is a perspective view of a breath test ventilation apparatus of the present invention;

FIG. 2 is an in use view of a breath test apparatus of the present invention, carried by a breath testing apparatus (not claimed);

FIG. 3 is a bottom perspective view of a breath test apparatus of the present invention;

FIG. 4 is a side view of a breath test apparatus of the present invention; and,

FIG. 5 is a top view of a breath test apparatus of the present invention.

In the drawings, the broken lines depict unclaimed subject matter only and form no part of the claimed design.
